ARTIST'S PALETTE

Carl B. Sundberg, 59 Hourigan Drive,
Meriden, Conn. 06450

Filed Oct. 1, 1965, Ser. No. 87,261

Term of patent 14 years

(Cl. D74—1)

Fig. 1

Fig. 2

Fig. 3

FIG. 1 is a top perspective view of an artist's palette showing my new design;

FIG. 2 is a top plan view thereof; and

FIG. 3 is a side view of the same.

I claim:

The ornamental design for an artist's palette, substantially as shown.

D. 192,694 5/1962 Swett ----- D44—10
D. 193,244 7/1962 Bliss ----- D44—10
1,468,563 9/1923 Girard.
